UNITED STATES PATENT OFFICE.

HARRY P. MACDONALD, OF MONTCLAIR, NEW JERSEY, ASSIGNOR TO THE SNEAD & CO.
IRON WORKS, OF JERSEY CITY, NEW JERSEY, A CORPORATION OF NEW JERSEY.

SAND-HANDLING APPARATUS.

1,127,471.

Specification of Letters Patent.

Patented Feb. 9, 1915.

Application filed July 28, 1914. Serial No. 853,833.

To all whom it may concern:

Be it known that I, HARRY P. MACDONALD, a citizen of the United States, residing at Montclair, in the county of Essex and State 5 of New Jersey, have invented certain new and useful Improvements in Sand-Handling Apparatus, of which the following is a specification.

This invention relates to apparatus for handling sand and similar granular material, 10 but it has particular reference to devices for handling and treating sand preparatory for use in metal founding operations, especially in foundries where the sand is stored overhead. In general, my invention has for its 15 primary object the provision of an improved apparatus of simple and economical construction whereby sand may be transferred and prepared for immediate use with great rapidity and with a minimum number of 20 operations. Another object of my invention resides in the provision of an improved apparatus for feeding and riddling sand into a flask or similar receptacle with evenness 25 and uniformity, and my invention also contemplates the provision, in conjunction with the foregoing, of improved means for guiding or directing the sand discharged from the riddle into the flask.

The foregoing, together with such other objects as may hereinafter appear or are incident to my invention, I attain by means of a construction which I have illustrated in preferred form in the accompanying drawings, wherein—

Figure 1 is a vertical section through my improved apparatus; Fig. 2 and Fig. 3 are sections taken on the lines II—II and III—III respectively, of Figure 1; Fig. 4 is 40 a plan view of a detail part of my invention; and Fig. 5 is a plan view of a modification of my invention.

The general arrangement of my improved apparatus is shown in Fig. 1 from inspection 45 of which it will be seen that I employ a sand storage means, such, for example, as the hopper A, immediately beneath which is a riddling device B. Beneath the riddling device is a guide chute C which directs the course of the sand so that it falls into the flask D.

The riddle B may be of any suitable type, but it preferably should be in the form of a trough-like frame 7 in the bottom of which is secured a foraminous member, such as a 55 screen 8, the riddle being positioned so as to surround the discharge end 9 of the hopper, with the screen closely adjacent thereto. The riddle is reciprocated by means of the connecting rod 10 operated by the crank 60 shaft 11 of the motor 12. In order to hold the main portion of the sand out of direct contact with the screen 8, I provide a plurality of bars 13 which extend across the discharge opening in the hopper, as shown 65 and described in my co-pending application Serial No. 842,052, filed June 1, 1914.

The guide chute is substantially rectangular in cross section and its walls 14 flare outwardly at the top so as to catch any sand 70 that is carried past the edges of the hopper by the riddle. Located within and extending transversely of the chute are a plurality of guide or deflecting plates 15, which deflect the sand discharged from the riddle so that 75 it falls substantially straight down. The function of these plates will be clear when it is seen that the reciprocating riddle, which moves with considerable velocity, projects the particles of sand discharged at an angle 80 to the vertical, and in the absence of such deflecting means the sand would be scattered over a wide area. As indicated in Fig. 3, the plates 15 may be adjustably supported in the walls of the chute by means of the trunnions 16 and nuts 17. By loosening the nuts 85 the angle of the plates may be varied so as to deflect greater quantities of sand to a given portion of the flask, which is of considerable value in some classes of work.

In order to catch any stray sand, I provide a funnel-shaped member E which is placed upon the top of the flask D in the manner indicated in Fig. 1. I prefer to place a foraminous member, such as a screen 95 18, above the member E, the purpose of which will appear from the following: In some cases the sand discharged from the overhead storage means will have considerable distance to fall, and it will therefore 100 attain a velocity which will cause it to impact with a force sufficient to pack or ram

the sand between the cross bars 19 which are ordinarily provided in flasks. The effect of this is that when other ramming means are employed in finishing the mold, 5 soft spots are left beneath the bars. The screen 18 acts as a check to break the fall of the sand and deposits it in a uniformly compact mass, although—as has been pointed out—the depth of the sand itself may be 10 varied. It is also to be noted that the sand as it leaves the riddle and the chute falls in showers of fine grains and not in lumps, and consequently, it will not lodge on the top of the screen, but will pass through. 15 While the specific means for supporting the riddle, guide chute, and motor, do not form a part of my present invention, in order to illustrate some of the advantages of my improvement, I have shown the hopper 20 supported on an overhead sand floor 20, from which is hung a suitable framework 21 on which the guide chute, riddle and motor 20 are supported. The flask may be directly supported on any suitable molding device 25 F, as diagrammatically indicated.

There are many advantages obtained by this apparatus. The riddle acts as a gate when it is idle and sand is discharged from the hopper only when the riddle is operated, 30 and therefore, riddling of the sand immediately before use in the flasks is insured, thereby rendering the sand free from lumps and foreign matter. That this is the case will be seen from the fact that the sand is 35 agitated three times and screened twice, and this in one continuous operation. Another advantage of the combination is that the sand can be drawn for immediate use directly from the overhead sand floor, thereby 40 doing away with a number of different operations necessary in the usual foundry practice in preparing the sand for use. Furthermore, it eliminates the hand riddling of facing sand over the flask, and also other 45 analogous operations. The device is simple in construction and accomplishes its work with great rapidity; it requires only a minimum of space and is so arranged as not to interfere with the workmen.

50 A further development of my invention is illustrated in Fig. 5 from inspection of which it will be seen that the screen 18' (which corresponds in function to the screen 18 already described) does not extend entirely over the guide member E, as a result of which sand will fall into the uncovered positions without having its progress interrupted. The sand will therefore pack itself in those portions to a considerable degree of hardness, as compared with the other portions of the flask covered by the screen. This has been found to give superior results in certain kinds of molding,

such for example as the manufacture of soil pipe in which it is desirable to have the sand much harder over the core prints of the soil pipe.

1. claim:

1. In a foundry system the combination of a foundry floor, an overhead sand storage 70 floor having a discharge means, and a movable riddling device for controlling the discharge of sand, said riddling device acting as a gate when idle and as a combined discharging and riddling member when operated.

2. In a foundry system the combination of a foundry floor, a flask supported from said floor, an overhead sand storage floor 75 having a discharge opening adapted to discharge sand into the flask, and a movable riddling device controlling said opening and adapted to act as a gate when idle and to discharge and riddle the sand when operated.

3. In a foundry system, the combination of a foundry floor, a flask supported therefrom, an overhead sand storage floor adapted to discharge sand directly into the flask, and a foraminous member located in the 90 path of the sand discharged and adapted to arrest the fall of the sand and thereby prevent the packing of the sand in the flask.

4. In a foundry system, the combination of a sand flask on the foundry floor, an 95 overhead sand storage floor having a discharge opening, a reciprocating riddling device below said opening, and a guide chute beneath the riddling device located a substantial distance above the flask and adapted to deflect the sand discharged from the riddling device so that it will fall into the flask, the point of discharge from said chute being located a substantial distance above the flask whereby unobstructed access is had 100 to the flask for the handling thereof.

5. In a foundry system, the combination of a sand flask on the foundry floor, an overhead sand storage floor having a discharge opening, a reciprocating riddling device below said opening, a guide chute beneath the riddling device adapted to deflect the sand discharged from the riddling device so that it will fall into the flask, and a 110 foraminous member located in the path of the sand discharging from the chute to break the fall of the sand and prevent packing of the sand in the flask.

6. A sand handling apparatus comprising in combination an overhead sand storage means having a discharge opening from which the sand falls a substantial distance to the point of use, a reciprocating riddle located adjacent to said opening and a guide chute just beneath the riddle adapted to deflect the sand discharged by the riddle as it 120

125

reciprocates so that it falls within a limited area, the discharge end of the chute being located a substantial distance overhead relative to the point of use whereby unobstructed access is had to the sand at the point of use.

7. A sand handling apparatus comprising in combination an overhead sand storage means having a discharge opening from 10 which the sand falls a substantial distance to the point of use, a substantially horizontally reciprocating riddle adjacent thereto, and means adjacent to the riddle for deflecting the sand discharged by the riddle so that 15 it falls substantially vertically within a limited area.

8. A sand handling apparatus comprising in combination a sand storage means having a discharge opening, a substantially 20 horizontally reciprocating riddle, and means for deflecting the sand discharged by the riddle so that it falls substantially vertically within a limited area comprising a chute provided with a plurality of substantially vertical baffles.

9. A sand handling apparatus for foundries comprising in combination a substantially horizontally reciprocating riddle located a substantial distance above the 30 foundry floor so that the sand falls a substantial distance to the point of use, and means located therebeneath for deflecting the sand discharged by the riddle so that it falls substantially vertically within a limited area, the discharge end of said means being located a substantial distance above the point of use.

10. A sand handling apparatus comprising in combination a substantially horizontally reciprocating riddle, and means located 40 therebeneath for deflecting the sand discharged by the riddle so that it falls substantially vertically within a limited area, comprising a chute having an adjustable 45 baffle wall.

11. A sand handling apparatus comprising in combination a substantially horizontally reciprocating riddle, and means located therebeneath for deflecting the sand discharged by the riddle so that it falls substantially vertically within a limited area, and means located in the path of the falling sand to break the fall of the sand and prevent packing of the sand.

55 12. A sand-handling apparatus comprising in combination a flask, a sand feed therefor located above the flask, and an interposed foraminous member adapted to break the fall of the sand, said member 60 leaving a portion of the flask uncovered, whereby the sand in said portion will pack to a harder degree than the sand in other portions of the flask.

13. A sand-handling apparatus comprising in combination a flask, a sand feed 65 therefor located above the flask, and means in the path of the sand adapted to break the fall of portions thereof whereby in parts of the flask the sand will be packed harder than in others.

70 14. In apparatus of the class described, the combination of a flask to be filled with sand, and means above the flask for directing the course of the sand whereby the sand packs itself harder in some portions of the 75 flask than in others.

15. In apparatus of the class described, the combination of a flask to be filled with sand, and means in the path of the sand adapted to impede the progress of portions 80 thereof whereby the sand in parts of the flask is packed harder than in other parts.

16. In apparatus of the class described, the combination of a flask to be filled with sand, and variable means above the flask 85 adapted to direct the course of the sand whereby more sand is delivered to some portions of the flask than to others.

17. In a foundry system, the combination of a sand receiving receptacle located adjacent to the foundry floor, a sand discharge means adapted to discharge sand into said receptacle, and means in the path of the sand discharged located above said receptacle and substantially adjacent thereto adapted to break the fall of the sand, the point of sand discharge being at a point a substantial distance overhead relative to the said means for breaking the fall of the sand.

90 18. In a foundry system, the combination of a flask located adjacent to the foundry floor, an overhead sand storage means adapted to discharge sand into the flask for direct use, and a foraminous means located 95 above and adjacent to the flask adapted to break the fall of the sand discharged to prevent packing thereof in the flask, the point of discharge from said storage means being located a substantial distance overhead 100 relative to the said foraminous means.

19. In a foundry system, the combination of a sand receiving receptacle adjacent the foundry floor, a sand discharge means adapted to discharge sand into said receptacle having a point of discharge at a substantial distance above the receptacle, and a readily removable member carried on the said receptacle adapted to break the fall 115 of the sand discharged from said discharge means.

20. In a foundry system the combination of a sand discharge means, a sand receiving receptacle, and a member immediately above the receptacle adapted to break the fall of 120 the sand being discharged to prevent the 125

sand from packing in the receptacle, said receptacle and said member being relatively readily removable so as to be freely brought into and out of operative relation, the said discharge means having a point of discharge a substantial distance above both the receptacle and the said member whereby to facilitate handling.

In testimony whereof I have hereunto signed my name in the presence of the two above subscribed witnesses:
